UNITED STATES PATENT OFFICE.

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI.

PAINTING APPARATUS.

Application filed October 18, 1924. Serial No. 744,335.

This invention relates to paint pots and with regard to certain more specific features, to pots for holding paint under pressure and for delivering the same under a constant pressure.

Among the several objects of the invention may be noted the provision of a device of the kind described which shall keep its contents under a pressure, shall deliver them at predetermined and adjustable pressures which remain constant after adjustment, shall deliver air at predetermined constant pressures, and the provision of such a device which is simple to manufacture and not readily clogged while in operation. Other objects will be in part obvious and in part pointed out hereinafter.

The invention accordingly comprises the features of construction, combinations of elements and arrangements of parts, which are exemplified in the description hereinafter in connection with the accompanying drawings, and the scope of the application of which will be indicated in the following claims.

In the accompanying drawings, in which are illustrated two of various possible embodiments of the invention,

Fig. 1 is a side elevation of a preferred embodiment of the invention and,

Fig. 2 is a top plan view of Fig. 1. Referring now more particularly to Fig. 1 there is illustrated at 1 a paint pot of simple construction comprising a cylinder with a smooth flat bottom. It may be cast or stamped, but in the present embodiment an aluminum casting is preferred.

The pot 1 is provided with a cover 3. A groove 5 in the cover 3 receives a gasket 7. The cover 3 is mounted on the pot 1 by means of the groove 5, and the gasket 7, within said groove becomes a sealing member between pot and cover.

The cover may be drawn down tightly on the pot by means of draw-studs 9. These are threaded, pass through open-ended slots in lugs 11 and are provided with wing nuts 13 above said lugs. At their lower ends they are provided with eyes and are pinned to lugs 15 formed integrally with the pot. The lugs 11 form part of the cover. By this means the cover may be drawn down tightly upon turning the wing nuts and the interior of the pot made air tight. When the cover is off, the

draw-bolts 9 swing downwardly and out of the way.

The cover 3, itself, is provided with several novel features. It is the purpose of the apparatus, as here embodied, to have one intake valve for air, to send air obtained through this valve through two branches; one in which it passes through a regulator for governing the pressure on the paint within the pot and the other in which it passes through a regulator governing the pressure within an air manifold. The paint is to be drawn off from the vessel from a single port 70 and some of the air (that which never enters the pot) from two ports of the manifold. The reason for this arrangement is the use of two types of spraying devices to be fed by the device under consideration. One of the spraying devices requires both a pressure-fed air line and a pressure-fed paint line, while the other requires a pressure-fed air line only. The latter device carries its own paint or liquid supply and has a gravity feed for the same.

In accordance with the above purpose there are mounted on the cover, two pressure regulators, one regulator 17 of high pressure capacity, and the other, 19, of low pressure capacity. The high pressure regulator 17 governs the air pressure to the spraying devices. It is fastened to the cover 3 by means of the standard 21, cast integrally with the regulator and bolted to the cover 3 with the bolt 23. This regulator has connected therewith, by means of nipple 25, the manifold 27. It is the air pressure in this manifold that the regulator governs. The manifold 27 has a gage 29 fastened thereto for reading pressures and two valves 31, 33 leading to outlets 35, 37 from which air is led to the spraying devices by flexible tubing.

The other low pressure regulator 19 has a standard 29 to which it is cast and by means of which it is fastened to the cover 3. The fastening here, however, comprises a nipple 45 and a passage is left through the cover so that air pressure may be conveyed to the inside of the pot. Both the high and low pressure standards 21 and 29 are hollow from end to end but in the case of the high pressure standard 21 the lower passage has been closed by bolt 23. In the upper passage of the low-pressure regulator 19 is screwed the L 41 to which is fastened the gage 43 for reading

pressures on the "low" side of the regulator 19, which is equivalent to reading the pressure within the pot.

Both regulators are of like construction, 5 but the low pressure one is so calibrated that it will not deliver over 40 pounds per square inch under a head of 125 pounds per square inch. Furthermore, the compressing device is so proportioned that at no time can it compress more than to approximately 170 pounds per square inch. This obviates the danger of an explosion. The pressure in the manifold 27 may be carried much higher as its small size permits of ample metal thickness, for 15 the pressures carried. Thus it is evident that one design of regulator serves for both high and low pressures. Also, the gages may be duplicates. This duplication lends itself to economical manufacture.

20 Nipples 49 and 51 connect both regulators to a common air inlet valve 53 to which is led high pressure air.

The air from the low pressure regulator passes into the pot by way of nipple 45 and 25 the U-tube 55, which tube ends upwardly into a blind hole 57 bored into the cover 3. This hole is only slightly larger than the tube and the tube has a slight end-clearance. The object of this is to provide a pocket of air 30 around the end of the tube which when compressed by splashed slugs of paint (assuming the bucket to be roughly handled) does not permit said slugs to enter and clog the tube to the regulator or get into the regulator itself. This action is facilitated in that a paint 35 film forms between the tube 55 and the lower edge of the hole 57.

The pot is also provided with a hole 58 into 40 which is screwed on the outside the blow-off cock 59 for releasing the pressure in the pot preparatory to refilling it. The hole 58 is also provided with an inwardly extending U-tube 61 which ends upwardly in the blind hole 63. The function of this tube and hole 45 is the same as that of tube 55 and hole 57 and prevents paint mist from blowing into the atmosphere when pressure is released.

Paint or liquid is drawn from the pot by 50 means of the vertical tube 65, screwed into a pocket 67 of the cover. Screwed into and leading to this pocket is the horizontal cock 69 which is adapted to receive a flexible paint line. The vertical pipe ends near the bottom 55 of the pot thus making it possible to draw off practically all of its contents. Heretofore liquid has usually been drawn from the bottom by arranging an outlet in the bottom itself. This multiplies and complicates the 60 constructive work to be done on said pot bottom.

A safety valve 71 is provided in the cover for over pressures.

The operation of the pot is as follows:

65 The pot is filled to a predetermined level with, say paint. The cover is applied and

clamped down with the draw bolts 9 and wing nuts 13 cooperating with the outstanding lugs 11. The device is now air tight. An air pressure line is connected to the valve 53 carrying say 125 lbs. per square inch. A 70 paint line is connected to the outlet valve 69. This leads to a paint gun which has an air line connecting with the valve 31 of the air manifold 27. Thus this paint gun receives both air and paint from the present device. 75 It is required that the paint come at a lower pressure than the air and that both have constant pressures.

Another paint gun has an air line connected 80 with the valve 33 of the manifold 27 but receives no paint as it has its own separate gravity-fed supply.

The pot is now ready for operation. All the valves are opened. The low-pressure regulator is adjusted to, say 40 pounds per square 85 inch. Air passes into the valve 53 at, say 125 pounds per square inch, some through the low pressure regulator, standard 39, nipple 40, U-tube 55, blind hole 57 and into the interior of the pot exerting a pressure of 40 90 pounds per square inch after having been reduced in pressure in the regulator. The paint is thus forced up the pipe 65, through the passage 61, valve 69 and to the paint gun already referred to.

Meanwhile some of the high pressure air (125 pounds per square inch) has gone through the nipple 51 to the high pressure regulator 17, through the standard 21, up 95 through the nipple 25, into the manifold 27 and out the valves 33 and 31 to the respective guns, having been reduced in pressure to say 100 pounds per square inch. The operation 100 will continue until the paint level drops to the bottom of the vertical tube 65.

To cease operations the valves are turned off and the cock 59 opened, whereupon the pressure is released within the pot without spraying paint into the air.

The cover may now be removed and the 110 pot emptied, or refilled for further use. It is evident that the cock 59 and regulator 19 are two of various types of operating accessories which may be fastened to a vessel, and that the improved U-tubes may be applied to like 115 accessories where air is to be passed, but not liquid.

From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

I claim:

1. In a pressure vessel provided with accessories for functioning with air, said 130

- accessories communicating internally with said vessel, the combination of, U-tubes leading from said accessories to within the vessel and blind holes provided within said vessel 5 for receiving the ends of said tubes.
2. In a pressure vessel provided with accessories for functioning with air, said accessories communicating internally with said vessel, the combination of tubes leading from 10 said accessories to within the vessel and blind holes provided within said vessel for receiving the ends of said tubes.
3. In a device of the type described the combination of a sealed vessel, a regulator 15 thereon adapted to regulate pressures therein, an air manifold thereon, a second regulator adapted to regulate pressure in said manifold, a blow-off valve on said vessel, U-tubes within said vessel connected with said first 20 named regulator and with said blow-off valve and blind holes within said vessel for receiving the ends of said tubes.
4. In a device of the type described the combination of a sealed vessel, a regulator 25 thereon adapted to regulate pressures therein in an air manifold thereon a second regulator adapted to regulate pressure in said manifold, a blow-off valve on said vessel, tubes within said vessel connected with said first 30 named regulator and with said blow-off valve and blind holes within said vessel for receiving the ends of said tubes.
5. In a pressure paint vessel comprising a pot and cover, the provision in combination of a pressure regulator on said cover adapted to 35 regulate the pot pressure, a blow-off cock on said cover, blind holes on the inside of said cover, pipes within said pot and on said cover connected with said cock and regulator respectively and extending into said holes 40 for the purpose of preventing passage of paint to the cock or regulator, an air manifold on said cover and another regulator therefore, means for drawing paint from the bottom of said pot through said cover means 45 for reading the low-side pressure of each regulator and a safety valve on said cover.
6. The pressure vessel comprising a pot, a removable cover therefor, at least one accessory connected to said cover for functioning 50 with air, at least one tubular portion leading from said accessory to within the vessel and at least one blind hole provided within said cover for receiving one end of said tubular portion, the cover, accessory and tubular portion being movable as a unit.

In testimony whereof, I have signed my name to this specification this 16th day of October, 1924.

THEODORE BIRKENMAIER.
